(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

The bracelet comprises a strap forming a double turn, closed by an essentially D-shaped buckle; the bracelet further comprises a pass-through cage, which is arranged on the end of the strap close to the buckle and into which the other end of the strap is threaded; on the outside, the pass-through cage has an H-shaped pattern turned by 90 degrees.

1 Claim, 7 Drawing Sheets
